UNITED STATES PATENT OFFICE.

DENNIS E. VIRTUE, OF MINNEAPOLIS, MINNESOTA.

ENSILAGE-CUTTER.

1,363,445.

Specification of Letters Patent. Patented Dec. 28, 1920.

Application filed April 10, 1920. Serial No. 372,944.

To all whom it may concern:

Be it known that I, DENNIS E. VIRTUE, a citizen of the United States, residing at Minneapolis, in the county of Hennepin and State of Minnesota, have invented certain new and useful Improvements in Ensilage-Cutters; and I do hereby declare the following to be a full, clear, and exact description of the invention, such as will enable others skilled in the art to which it appertains to make and use the same.

My invention has for its object to provide an improved ensilage cutter, and to such ends, the invention consists of the novel devices and combinations of devices herein-after described and defined in the claims.

As illustrated in the drawings, the ensilage cutter is designed to be carried on a truck, so that it is readily portable from place to place, but so far as the invention is concerned, it may be either portable or fixed.

The invention involves various features of novelty, but the novelty is chiefly in an improved arrangement of the means for supporting and driving the ensilage cutter, which latter is preferably a combined cutter and fan head. As a salient novel feature, I employ a tubular fixed spindle, extend a shaft through this spindle and mount a driving sleeve on the exterior of the spindle. The shaft and the driving sleeve are connected for simultaneous rotation at one end of the fixed spindle. The sleeve carries a driving pulley, or the like, and also the head, which latter carries the ensilage cutting knife and the fan blades. The shaft that is extended through the fixed spindle, at its extended end, transmits motion to mechanism that drives the ensilage feeding device, consisting preferably of coöoperating feed rollers and an endless feed belt. The mechanism last noted, also comprises a reversible variable speed gear mechanism for driving the ensilage feeding devices.

The invention is illustrated in the accompanying drawings wherein like characters indicate like parts throughout the several views.

Referring to the drawings:

Figure 1 is a plan view of the ensilage cutting machine, some parts being removed.

Fig. 2 is a vertical section taken substantially on the line 2—2 of Fig. 1;

Fig. 3 is a section taken approximately

on the line 3—3 of Fig. 1 and showing the reversible variable speed gear mechanism;

Fig. 4 is a transverse section taken on the line 4—4 of Fig. 2;

Fig. 5 is a view partly in plan and partly in horizontal section and with some parts broken away, showing particularly the manner in which the fixed spindle is supported and in which the shaft and driving sleeve and various other parts are mounted in connection therewith;

Fig. 6 is a fragmentary view illustrating the manner in which the fixed spindle is anchored to the gear housing which supports the same, all of the running parts being removed; and

Fig. 2^a is a diagrammatic elevation of certain driving connections.

For supporting the driving gears, feed rollers, shearing blade and combined fan head and ensilage cutting knife, and certain other parts, I provide what I designate as a bed frame. This bed frame comprises, as shown, a transversely extended casting 7 having a gear box or housing 8 cast integral therewith. The ends of the frame casting 7 are downwardly extended to form laterally spaced legs 9, to which a rear axle 10 is secured, the rear wheels 11 being journaled on the ends of this axle.

The front wheels 12 are journaled to a front axle 13, which, at its central portion, is connected by a knuckle joint 14 to a stem 15 that is swiveled in a tubular column 16, the upper end of which latter is rigidly secured to the front end of a long and quite large pipe 17 that constitutes what is herein designated as a reach. This tubular reach, at its rear end, closely fits into a semi-cylindrical seat 18 formed on the gear box 8; and the rear end of said reach is rigidly connected to said gear box by bolt-secured anchoring straps 19, or any other suitable means that will rigidly secure said reach to the gear box, and hence, to the bed frame 7.

The bed frame 7, at one side of the gear box 8, is provided with a horizontal ledge 20, to which, by screws 21, or the like, the fixed shearing blade 22 of the ensilage cutter is rigidly secured.

As a bearing for the combined fan and movable cutter, and for certain other parts, I employ a tubular fixed spindle 23 that is cast integral with, or otherwise, rigidly

secured to the frame casting 7 and projects both forward and rearward of the upstanding flange thereof, as best shown in Fig. 5. This fixed spindle 23 lies quite close to one end of the shearing blade 22 and its axis is horizontally disposed at ninety degrees to the cutting edge of said blade.

Mounted to rotate upon the rear end portion of the fixed spindle 23 is a sleeve 24, herein designated as the driving sleeve, and this sleeve is provided at its rear end with a pulley 25 over which will run a power driven belt, not shown, but which will transmit all of the power of the running parts of the machine. The arrangement shown contemplates the use of the engine and driving belt, but if the machine is to be driven by an electric motor, it might be possible to apply the armature or rotor thereof, directly to the sleeve 24, in lieu of the pulley 25. Preferably, and as shown, Timken bearings 26 which resist thrusts, as well as reduce friction due to rotation are interposed between the sleeve 24 and spindle 23. The numeral 27 indicates a cap that is bolted, or otherwise rigidly but detachably secured to the pulley 25; and this cap is rigidly secured to the rear end of a driving shaft 28 that is extended axially through 30 and is journaled in the fixed spindle 23. At the rear end of the spindle, a roller bearing 29 is shown as interposed between the said shaft and spindle, and this shaft, at its rear end, is equipped with a worm 30 that is located within the rear end of the tubular reach 17.

The worm 30 is in mesh with a worm gear 31, which, as shown, works through a slot in the bottom of the tubular reach 17 and 40 in the seat 18. This worm gear is rigidly secured to a countershaft 32 that is journaled in suitable bearings afforded by the gear box 8 and projects therefrom at one end (see particularly Fig. 4). The extended 45 end of shaft 32 is surrounded by a long sleeve 33 that is capable of sliding and oscillatory movement on said shaft, and at its outer end is provided with a lever 34, the purpose of which will presently appear. At its inner end, the sleeve 33 is provided 50 with a shipper head 35 to the lower arm of which an intermediate gear 36 is journaled. This intermediate gear 36 meshes with a gear 37 that is keyed to rotate with the shaft 32, but is free to slide thereon and is adapted 55 to be shifted axially by the head 35. The numeral 38 indicates a gear that is free to rotate on the shaft 32, but is held against sliding movements by a lug 39 on the gear 60 box 8, (see Fig. 4). The gears 37 and 38 are provided with coöoperating half clutches 40 that are adapted to be engaged, as hereinafter described.

By oscillatory and sliding movements of 65 the sleeve 33, accomplished by manipula-

tions of the lever 34, the intermediate gear 36 (see Figs. 1 and 3) is adapted to be engaged at will with any one of three different sized gears 41, 42 and 43 keyed to rotate with a shaft 44, is journaled in the gear 70 box 8 and is extended and also journaled in a fixed frame bar 45. The extended portion of the shaft 44 (see Figs. 1 and 2), carries a toothed or corrugated feed roller 46 that works closely adjacent to the rear 75 edge of the fixed shearing blade 22. The loose gear 38 runs in mesh with a similar gear 38^a (see Fig. 1), that is also secured to the shaft 44.

A driving sleeve 24, already described, 80 carries the fan head and the ensilage cutting knife. The fan head (see Figs. 1, 2 and 5) comprises a disk 47 that carries the fan blades 48, and also carries the ensilage cutting knife 49, the latter being positioned 85 to pass in close contact with the cutting edge of a fixed blade 22. There may, of course, be any desired number of these knives 49, but only one is shown in the drawings.

From the above, it will be seen that, by 90 the sleeve mounted on the exterior and the shaft journaled at the interior, of the fixed spindle 23, the fan and ensilage cutter are operated from the first noted element and the transmission of power for driving the 95 feeding mechanism is effectually accomplished from a single driving element, such as a driving pulley. Moreover, the arrangement is such that there is no possibility of the wheel or element that carries the knife 100 or knives getting out of alignment with the fixed shearing blade. Also, a long compact construction is afforded in which the driving shaft is free from the load in the action of the fan head.

The fan head and the movable ensilage cutting knife or knives, are arranged to work within the fan casing 50 suitably supported from the framework 7 and provided with the customary tangential discharge 110 spout, through which, under the action of centrifugal force, and the blast from the fan, the cut ensilage will be discharged in a well-known manner.

For feeding the corn stalk to the cutter, 115 I have shown an endless feed belt 52 arranged to run over sprockets 53 and 54, respectively, on shafts 55 and 56. The shaft 55 is journaled in the frame bar 45 and in a similar fixed frame bar 45^a, (see Fig. 1), 120 while the shaft 56 is journaled in the extended end of a trough-like conveyer frame 57 that is suitably secured to the reach 17 and certain other parts of the machine and has a deck 58 over which the upper portion 125 of the feed belt 52 is arranged to travel.

The shaft 44, to which toothed feed roller 46 is secured, is provided at its extended end (see Figs. 1 and 2^a), with a sprocket 59 that is aligned with a sprocket 60 on the end 130

of the shaft 55 and with a sprocket 61 on the frame bar 45. A sprocket chain 62 runs over the three alined sprockets 59, 60 and 61, and thus transmits motion from the 5 roller shaft 44 to the sprocket shaft 55, thereby driving the feed belt 52. Sprocket 60 has an extended hub that carries a spur gear 63 that meshes with a spur gear 64 (see Figs. 2^a and 4), that is loosely journaled to 10 the upwardly extended end of the frame bar 45, and on its hub carries a sprocket 65.

The numeral 66 indicates a floating upper feed roller that works just above the feed roller 46. This feed roller 66 is journaled to 15 the rear ends of a pair of parallel links 67 that are pivoted to the upper end portion of the frame bars 45 and 45^a at points concentric to the axis of spur gear 64 and sprocket 65. The roller 66 has a shaft 66^a which, at 20 one end, is equipped with a sprocket 68, over which, and the sprocket 65, a sprocket chain 69 is arranged to run, so as to thereby impart a rotary motion in the proper direction to the upper roller. Obviously, the two feed 25 rollers will be rotated in reverse directions so as to produce the proper feeding movement to the ensilage cutter of the stalks delivered to the rollers by the feed belt.

It is now evident that by adjustments of 30 the movable intermediate gear 36 into mesh with any one of the three gears 41, 42, 43, the feed rollers 46 and 66 and the feed belt 52 may be driven in a forward direction at various different speeds, in respect to the 35 speed of rotation of the combined fan and ensilage cutter. It will also be evident that when the gear 37 (see Fig. 4) is slid to the left so that the half clutches 40 will be engaged, the shaft 32 will then be directly 40 connected to gear 38 and the direction of travel of the feed devices will then be reversed.

For effecting the above adjustments of the reversible variable speed gear mechanism, the operating lever 34 is preferably arranged to coöperate with a latch plate 70 (see Fig. 1) that is rigidly secured to the frame 7. This latch plate 70 has a lever passage 71 that is formed with offset 50 steps 72, 73, 74 and 75. When lever 34 is engaged with step 72, gear 36 will be engaged with small gear 41, and feed devices will then be driven forward at the highest speed; when lever 34 is engaged with step 73, gear 36 will be engaged with intermediate gear 42 and the feed mechanism will then be driven forward at intermediate speed; when lever 34 is engaged with step 74, gear 36 will be engaged with 55 the largest gear 43 and the feed mechanism will then be driven forward at the slowest speed; and when the lever 34 is engaged with step 75, gear 37 will be interlocked to

gear 38 and the feed mechanism will, as noted, then be driven backward. 65

For locking the lever 34 in any one of its said several adjustments, it is shown as provided with a long pivoted dog 34^a that is engageable, respectively, with stop lugs 72^a, 73^a and 74^a, on the plate 70. 70

What I claim is:

1. In a machine of the character described, the combination with a fixed tubular spindle, of a rotary member journaled in said tubular spindle, a second rotary member including a driving means journaled on said spindle and connected to rotate with said shaft, a stock cutter driven by one of said rotary members, and a feed mechanism driven by the other of said rotary members and operative to deliver stock to said cutter. 75 80

2. In a machine of the character described, the combination with a fixed tubular spindle, of a rotary shaft journaled in said tubular spindle, a rotary sleeve journaled on said spindle and connected to rotate with said shaft, a stock cutter driven by one of said rotary members, and a feed mechanism driven by the other of said rotary members and operative to deliver stock to said cutter, 85 90 and a power driven driving member directly connected to one of said two rotary members.

3. In a machine of the character described, the combination with a fixed tubular spindle, of a shaft extended therethrough and a 95 sleeve mounted thereon, a driving pulley on said sleeve, said shaft and sleeve being connected for common rotation, of feed mechanism driven from said shaft, and a fan operated from said sleeve, the connection between said shaft and feed mechanism including a worm on one end of said shaft and a worm gear meshing with said worm. 100

4. The combination with a frame member and a fixed tubular spindle rigidly secured thereto, of a rotary shaft journaled in said tubular spindle, a rotary sleeve journaled on said spindle and connected at one end to said shaft for common rotation therewith, two mechanisms, one driven from said shaft and 110 the other from said sleeve and a power driven driving element applied to said sleeve. 105

5. In a machine of the character described, the combination with a framework and a fixed tubular spindle rigidly secured thereto, 115 a shaft extended axially through and journaled in said spindle, a sleeve journaled on said spindle, a coupling head applied to said shaft and sleeve and coupling the same at one end for common rotation, a fan and 120 cutter head, and a feeding mechanism, one driven from said shaft and one from said sleeve, and a power driven means for rotating said sleeve and shaft.

In testimony whereof I affix my signature. 125
DENNIS E. VIRTUE.
